UNITED STATES PATENT OFFICE.

BEN MAZZA, OF GRAND JUNCTION, COLORADO.

IGNITING MECHANISM.

1,160,927.

Specification of Letters Patent. Patented Nov. 16, 1915.

Application filed January 30, 1915. Serial No. 5,293.

To all whom it may concern:

Be it known that I, BEN MAZZA, a citizen of the United States, residing at Grand Junction, in the county of Mesa and State 5 of Colorado, have invented new and useful Improvements in Igniting Mechanism, of which the following is a specification.

This invention has for its object the provision of an igniting mechanism primarily 10 intended for automatically lighting the fuel in a stove, furnace or the like at a predetermined period.

Among other features the invention embodies an igniting mechanism which can be 15 attached to or associated with the alarm mechanism of the ordinary and well known form of alarm clock, so as to operate on sounding of the alarm to ignite or start the ready laid fire in a stove, furnace or the like.

20 I further aim to provide a device for the above mentioned purpose which is simple in construction, durable and efficient in operation.

Other objects will appear as the nature 25 of the invention is better understood, the same consisting of the combination, construction and arrangement of parts herein-after more fully described.

In the drawing forming a part of this application like numerals of reference indicate similar parts in the several views, and in which;

Figure 1 is a perspective view of the rear 30 face of an alarm clock showing my invention applied thereto. Fig. 2 is a sectional view through the block and latch mechanism as shown in Fig. 1 and looking at right angles thereto.

Referring more particularly to the drawing 35 5 designates an alarm clock of the ordinary and well known construction, and 6 the winding key of the alarm mechanism.

Extending transversely across the rear 40 face of the clock is a shelf 7 forming a guide 45 for the ignition element 8 mounted for sliding movement thereon. The element 8 is in the nature of an elongated block normally held by a suitable latch means at one end of the shelf 7, retractile spring 9 being secured 50 to the forward end of the block and to the opposite end of the shelf for drawing the block across the rear face of the clock upon release of the said latch means. The block is formed with a roughened inclined upper 55 surface for igniting the match 10, which lat-

ter is disposed in the path of travel of the block.

The latch mechanism comprises an arm 11 pivoted at one end to the rear face of the clock above the shelf 7 and supported in 60 parallelism therewith by means of the winding key 6. Depending at a right angle from the opposite end of the arm 11 is a pin 12 adapted to be arranged within the recess 13 in the block 8 to normally retain the latter 65 in position at one end of the shelf against the action of the spring 9. Manifestly by reason of this arrangement when the alarm goes off the winding key 6 in turning moves the pin 12 upwardly allowing the block 8 70 to be drawn across the shelf causing an ignition of the match 10, the pin 12 moving in the guides 14.

The match as shown is supported by 75 means of a spring clamp 14' secured to the rear face of the clock above the shelf 7 and supports the match in the path of movement of the block 8. The clamp 14' may be of any contour, but as shown includes a resili- 80 ent limb terminating in an eye 15 for the reception of the match, which is rigidly supported therein by means of a set screw 16 to insure ignition of the same at the proper time. By reason of the inclination at which the match is supported, together with the 85 resiliency of the clamp 14', the latter is permitted to give sufficiently to compensate for the compact between the block 8 and the match when the former is drawn across the 90 face of the clock to igniting position, thus preventing breakage of the match.

Mounted on the rear face of the clock is a leaf spring 17 between which and the face of the clock is clamped the free end of a fuse 18 which leads to the fuel in the fire box of 95 a stove, furnace or the like.

The use of the device is as follows: The 100 alarm is first set for the time at which it is desired to light the fire, and the block 8 subsequently brought to and locked in the position shown in Fig. 1. The clock is then placed upon the ledge of the stove which projects from the base of the ash pit in the ordinary and well known form of stoves, or supported adjacent thereto on any suitable 105 support. A fuse made of any suitable material and leading from the fuel in the fire box of a stove is next clamped beneath the leaf spring 17. Now when the alarm goes off the winding key 6 in turning lifts the pin 110

12 out of the recess 13 allowing the block to be drawn by the spring across the shelf, thus igniting the match 10 during its course of travel. The flame of the match as is obvious 5 ignites the fuse which in turn ignites the wood, paper or other inflammable material which is supported upon the grate of the stove.

While I have shown and described what I 10 now consider the preferred form of my invention, I desire to have it understood that the same is merely illustrative, and that various changes in the construction and arrangement of parts may be resorted to when 15 desired as fall within the scope of the appended claims.

What I claim is:—

1. The combination with a clock mechanism, of a transversely disposed slotted shelf 20 supported on the rear face of the clock, an ignition element on said support and including a block having a roughened inclined upper surface, a pin depending from said block through said slot, a spring connected 25 with said pin and one end of the shelf for moving said block in one direction upon said shelf, a spark producer made active by

said element on movement thereof, and a time controlled means for holding said element immovable against the first mentioned 30 means.

2. The combination with a clock mechanism, of a transversely disposed shelf secured to the rear face of the clock, an igniting element movably supported upon said shelf, means for moving said element in one direction, a spark producer made active on movement of said element, a time controlled means for holding said element immovable against the first mentioned means, and including a pivoted arm supported upon the winding key of the clock mechanism, a second arm depending therefrom for engagement with said element, and said winding key being adapted to actuate said means to 40 release said element at predetermined periods.

In testimony whereof I affix my signature in presence of two witnesses.

BEN MAZZA.
